UNITED STATES PATENT OFFICE.

EDWIN E. LEHR, OF WILKINSBURG, PENNSYLVANIA, ASSIGNOR TO WESTINGHOUSE ELECTRIC & MANUFACTURING COMPANY, A CORPORATION OF PENNSYLVANIA.

REGULATOR SYSTEM.

Application filed September 16, 1921. Serial No. 501,144.

To all whom it may concern:

Be it known that I, EDWIN E. LEHR, a citizen of the United States, and a resident of Wilkinsburg, in the county of Allegheny and State of Pennsylvania, have invented a new and useful Improvement in Regulator Systems, of which the following is a specification.

My invention relates to regulator systems and it has special relation to means associated therewith to compensate for variations in a supply circuit by reason of variations in the load thereupon.

One object of my invention is to provide a compensatory means of the above-indicated character which shall be relatively simple and compact in construction and efficient and reliable in operation.

Another object of my invention is to provide means of the above-indicated character which shall compensate for inductive and ohmic line variations in steps of varying degree.

Reference may now be had to the accompanying drawing, wherein—

Figure 1 is a diagrammatic illustration of the circuits and apparatus embodying my invention; and

Fig. 2 is a front elevation of a control panel for the compensator.

The principles of the present invention will be described in connection with an induction regulator but it will be understood that such description is illustrative only.

An induction regulator of well-known construction is indicated at 1 and has a current coil 2 and a voltage coil 3. The regulator is controlled by a reversible motor 4, which is energized from conductors 5 connected to any convenient source of power, through gearing 10. Reversing switches 6 and 7 govern the operation of the motor 4 in the one or the other direction. The coils 8 and 9 of the reversing switches are respectively connected to contact members 11 and 12 which are controlled by the operation of a pivoted lever 13 having a control magnet 14 secured thereto. The coil 15 of electromagnet 14 is energized, in accordance with the voltage of the supply circuit, through a voltage transformer 16. The illustration of the induction regulator and its control apparatus is diagrammatic since its specific structure is not a part of the present invention.

A compensator 17 is connected in series

relation with the coil 15 of control magnet 14, and includes a transformer 18, the primary winding 19 of which is energized from the supply circuit through a current transformer 21. The leads 23 and 24 of the secondary winding 22 of transformer 18 are connected, respectively, to control levers bearing the same reference numerals and located upon the control panel 20 (Fig. 2), for a purpose to be hereinafter explained. A reactance coil 25, which constitutes the primary winding of a reactance transformer 26, is connected in series relation with the primary winding 19 of transformer 18. The winding 25 comprises a plurality of sections divided by a series of taps, indicated at 27, 28, 29, 30, 31, 32, 33, 34, 35 and 36. It will be noted that taps 27 to 31, inclusive, embrace relatively small sections of the winding 25, whereas taps 32 to 36, inclusive, embrace relatively large sections of the winding 25. The taps 27 to 36, inclusive, are electrically connected to the contact buttons 27 to 36, inclusive, of the control panel 20. Control levers 37 and 38 engage with the contact buttons 27 to 36 to determine the number of energized sections of the winding 25.

The secondary winding 39 of the reactance transformer 26 is connected in series relation with the coil 15 of the control magnet 14. A variable resistor 41, having a series of taps therefrom, indicated at 42, 43, 44, 45, 46, 47, 48, 49, 50 and 51, respectively, is connected in series relation with the secondary winding 39 and also in series relation with the coil 14 of the control magnet. It will be noted that taps 47 to 51, inclusive, embrace relatively small sections of the resistor 41, whereas taps 42 to 46, inclusive, embrace relatively large sections of the resistor 41. The taps 42 to 51, inclusive, are electrically connected to the contact buttons 42 to 51, inclusive, of the control panel 20. The control arm 24 selectively engages contact buttons 42 to 46, inclusive, and control arm 25 selectively engages contact buttons 47 to 51, inclusive.

It is well known that, when the distribution point is removed from the transmission line regulator, variations in load produce variations in drop in the feeder circuit. With the present invention, the compensation includes both reactance and resistance elements to maintain a constant voltage at the center of distribution. Also,

in the present invention, steps of different sizes enable variations of differing degrees to be effected.

When no compensation is required, the control arm 24 will engage contact button 46, and control arm 23 will engage contact button 47. Control arms 37 and 38 will respectively engage contact buttons 27 and 36. When maximum compensation is required, control arm 24 will engage contact button 42, and control arm 23 will engage contact button 51. Control arms 37 and 38 will respectively engage contact buttons 31 and 32. Obviously, any intermediate steps between no compensation and full compensation may be obtained, the control arms 38 and 24 giving relatively large steps of compensation, and control arms 37 and 23 giving the intermediate steps.

While the present invention is illustrated in connection with a single-phase circuit, it is obvious that it may be adapted for use in connection with polyphase circuits by well-known connections of the series and shunt transformers.

Modifications in the system and arrangement and location of parts may be made within the spirit and scope of my invention, and such modifications are intended to be covered by the appended claims.

I claim as my invention:—

1. In a regulator system for a supply circuit, the combination with an induction regulator having a reversible motor for operating said regulator and control means therefor energized in accordance with the voltage of said circuit, of means to compensate for load variations upon said circuit comprising a current transformer, a reactance transformer having a variable primary winding in series relation with said current transformer and a secondary winding, a variable resistor energized from said current transformer and connected in series relation with said secondary winding and with said control means, and means for varying said reactance transformer and said resistor.

2. In a regulator system for a supply circuit, the combination with an induction regulator having a reversible motor for operating said regulator and control means therefor energized in accordance with the voltage of said circuit, of means in circuit with said control means to compensate for load variations upon said circuit comprising a reactance transformer having a variable primary winding and a secondary winding, a variable resistor and means for varying said reactance transformer and said resistor.

3. In a regulator system for a supply circuit, the combination with an induction regulator having control means therefor energized in accordance with the voltage of said circuit, of means adapted to affect the op-

eration of said regulator to compensate for load variations upon said circuit comprising a plurality of transformers, one of which has a variable winding, a variable resistor and means for varying said transformer winding and said resistor.

4. In a regulator system for a supply circuit, the combination with a regulator having control means therefor energized in accordance with the voltage of said circuit, of means adapted to compensate for load variations upon said circuit comprising a series transformer, a variable reactance and a variable resistor in circuit therewith and with said control means and means for varying said reactance and said resistor.

5. A compensator for use upon a supply circuit subject to varying loads, said compensator comprising a current transformer, a reactance transformer having a variable primary winding in series relation with said current transformer and a secondary winding, a variable resistor in series relation with said secondary winding and means for varying said reactance transformer and said resistor.

6. In a compensator, the combination with a current transformer, of a reactance transformer in circuit with said current transformer and having a variable winding, a variable resistor in circuit with said reactance transformer and means for varying said reactance transformer and said resistor.

7. In a compensator, the combination with a current transformer, of a variable-reactance transformer and a variable resistor in circuit with said current transformer and means for controlling said reactance transformer and said resistor having control steps of different sizes.

8. In a compensator, the combination with a current transformer, of a variable-reactance device in series relation with said current transformer, a variable resistor in series relation with said reactance device and means for varying said reactance device and said resistor in steps of different sizes.

9. In a regulator system, the combination with a power circuit, a regulator connected thereto and means for controlling the operation of said regulator in accordance with a predetermined characteristic of said circuit, of means adapted to also control the operation of said regulator, said last mentioned means comprising a variable transformer element and a variable resistance element, and additional means for varying said elements.

In testimony whereof, I have hereunto subscribed my name this 29th day of August, 1921.

EDWIN E. LEHR.
